UNITED STATES. PATENT OFFICE.

EDWIN E. ANGELL, OF SOMERVILLE, MASSACHUSETTS.

INK-FONT.

1,104,861.

Specification of Letters Patent. Patented July 28, 1914.

Application filed October 9, 1912. Serial No. 724,866.

To all whom it may concern:

Be it known that I, EDWIN E. ANGELL, a citizen of the United States, and resident of Somerville, in the county of Middlesex and 5 State of Massachusetts, have invented certain new and useful Improvements in Ink-Fonts, of which the following is a specification.

This invention relates to ink fonts of the character in which the ink is contained in a substantially closed tilting tank or reservoir having its only outlet in a connection with an upwardly rising cup in which the ink 10 may be caused to rise by tilting of the reservoir.

The object of the invention is to provide an improvement in devices of this character according to which the pivotally mounted tilting ink tank may be easily removed from 15 its supporting base and at the same time will be prevented from being accidentally dislodged from the base and overturned.

In the accompanying drawings I have illustrated what I consider at present to be 20 the preferred form or embodiment of my invention.

Figure 1 is a plan view of an ink font embodying the invention. Fig. 2 is a side elevation of the same. Fig. 3 is a cross section 25 on line 3—3 of Fig. 1. Fig. 4 is a perspective view of one of the clips by which accidental dislodgment of the ink reservoir from the base is prevented.

The same reference characters indicate the 30 same parts in all the figures.

Referring to the drawings, *a* represents the base or pedestal which is flat on the bottom and is adapted to rest on a desk or table. It is hollow in its interior and has a raised 35 lip *b* similar in outline in plan view to the ink reservoir and surrounding a space somewhat larger in area than the reservoir.

c represents the ink tank or reservoir which is contained in the space inclosed by 40 the lip *p* and rises above the upper edge of such lip, as shown in Figs. 2 and 3. It is supported by alined trunnions *d* contained in notches *e* in the lip *b* and having bearings 45 on the bottoms of such notches. These trunnions pivotally support the ink tank, allowing the end to which the cup *f* is connected to be depressed when a pen is inserted in such cup and pressed downward. The center of gravity of the tank is on the side of 50 the pivotal axis opposite the cup *f* so the normal position of the tank is that shown in

the drawings, the tank being supported at its heavier end by a transverse bar *g* within the base against which a finger *h* projecting from the underside of the tank at its rear 55 bears. The part designated *i* is an elastic sleeve surrounding the finger *h* at that portion which bears on the brace *g* to soften the shock and deaden the noise when the finger strikes the brace. An adjustable stop *j*, in the form of a screw, is threaded through a boss *k* of the base in position to engage the upper side of the finger *h* when the cup is depressed.

The cup *f* is in communication with the interior of the tank through a narrow neck of the latter and provides the only outlet for the ink. The passage through the bottom of the cup is comparatively narrow and the ink is thus kept covered and protected from 60 dust and evaporation. It wells up through the bottom of the cup only when the latter is depressed by a pen inserted thereto.

l represents a cap threaded upon a nipple surrounding the filling orifice of the tank.

The notches *e* which provide bearings for the tank trunnions *d* are open, whereby to provide easy mounting of the tank on the base in the first instance and easy removal of the tank for filling. When the trunnions are in place they are prevented from being accidentally removed by clips *m* which are pivoted on studs *n* mounted in bosses *o* on the sides of the base. Each clip has a retaining portion *q* adapted to be 65 moved into a position across the notch *e* and over the trunnion *d* and with a handle portion *r* by which the clip may be swung about its pivot. In Figs. 1 and 3 one of the clips is shown in its operative position 70 for retaining the trunnion and the other is shown in its inoperative or open position. Preferably the clips are constructed as shown in detail in Fig. 4, being made of sheet metal stamped out in the proper shape 75 to make the eye *s*, the retainer *q*, the handle *r* and a lug *t* which overlies the end of the trunnion, and bent longitudinally on a line between the parts *q* and *t* so that the latter parts lie at right angles to each other in the 80 finished clip. The clips provide a secure means for retaining the tank upon the base, without interfering at all with its tilting function, and thereby preventing the tank from being accidentally dislodged. Without retaining means of suitable character it 85 is very easy to strike the prominent cup of

the tank in such a way as to knock the tank off of the base, causing it to fall on the table or desk, perhaps in an overturned position, with danger of spilling the ink on 5 papers or other things lying on the desk. With such retaining clips as I have illustrated there is no danger of such an accident occurring. On the other hand the 10 clips may be very readily swung aside, whereupon the tank may be removed for the purpose of refilling.

I claim:

1. An ink font comprising a base, a tank having an outlet at one end, said base having 15 a lip surrounding the tank and having notches, trunnions on the tank occupying said notches and pivotally supporting said tank in a manner such that the latter may be tilted to depress and raise its outlet, and 20 retainers mounted on the base and movable into positions closely overlying said trunnions, whereby to prevent accidental dislodgment of the trunnions from the notches, said retainers having lugs arranged to lie 25 across the ends of the trunnions.

2. An ink font comprising a tank having pivot trunnions and having an outlet at one side of the line of such trunnions, a base having open notches in which said 30 trunnions are contained and on the bottoms of which they have a bearing, and retaining clips mounted upon the base beside such

notches and movable across the latter over the trunnions and away therefrom, said clips having lugs arranged to close the outer 35 sides of the notches and cross the ends of the trunnions.

3. In an ink font, the combination of a base having a raised lip with open notches in its upper edge, said notches constituting bearings, and having a boss beside each notch, an ink tank having pivot trunnions contained in said notches, clips pivoted on said bosses, each clip being arranged to swing over the adjacent notch and having 45 a lug extending downwardly to cross the outer side of the notch and the end of the trunnion therein.

4. In an ink font including a tank having trunnions and a base having notches 50 receiving and constituting bearings for said trunnions, clips pivoted to said base beside said trunnions, each formed with a retaining portion and a lug depending from said retaining portion, said retaining portion overlying the notch and said lug crossing the end of the trunnion.

In testimony whereof I have affixed my signature, in presence of two witnesses.

EDWIN E. ANGELL.
